INVENTOR

Russell Brewer,
By his Attorneys, *Audison Smith*

UNITED STATES PATENT OFFICE.

RUSSELL BREWER, OF NEWARK, NEW JERSEY.

CAR-AXLE BOX.

SPECIFICATION forming part of Letters Patent No. 296,517, dated April 8, 1884.

Application filed January 16, 1884. (No model.)

To all whom it may concern:

Be it known that I, RUSSELL BREWER, a citizen of the United States, residing at Newark, in the county of Essex and State of New

5 Jersey, have invented certain new and useful Improvements in Car-Axle Boxes; and I do declare the following to be a full, clear, and exact description of the invention, such as will enable others skilled in the art to which 10 it appertains to make and use the same, reference being had to the accompanying drawings, and to letters or figures of reference marked thereon, which form a part of this specification.

15 Figure 1 of the drawings is a vertical longitudinal section, illustrating this invention. Fig. 2 is a vertical transverse section.

This invention has relation to car-axle boxes; and it consists in providing an interior oscillating bearing which will automatically adapt itself to the axle-journal, whatever may be the relative position of said journal and of the axle-box within which said bearing is located.

25 The invention also consists in combining with such interior oscillating bearings and the axle-journals anti-friction rollers.

The invention further consists in the construction and novel arrangement of the double 30 roller, and the convex oscillating bearing, operating in connection with said double roller, and a plane bearing in the upper part of the box; and the invention finally consists in providing, in connection with anti-friction rollers, elevator-lubricating devices adapted to 35 raise the lubricating material in a positive manner, all as hereinafter set forth.

In the accompanying drawings, the letter A designates the axle-box, which may be made 40 in the usual manner, except that it is provided in its upper portion with a chilled bearing, B, which is usually made plane. In front and rear of this bearing lugs c are located, and are perforated to receive the ends of a pin, d. 45 The chilled bearing B is centrally arranged in the top of the box, and is usually made entire therewith, as shown in the drawings.

D represents the journal end of a car-axle extending into the box. In front and in rear of 50 this journal are located lubricating-rollers E and F, which operate in connection with roll-

ers G and H, below them, the rollers G and H being partially or wholly submerged in the lubricating material in the bottom chamber, K, of the box.

55 L represents a double roller having the two roller-bearings m m, connected by a central cylinder or shaft, n. The roller-bearings and shaft of this double roller are chilled.

S indicates the oscillating bearing, which is 60 usually made with a chilled convex upper surface, p, which is designed to bear against the plane bearing B in the top of the box. The lower bearing-surface, t, of this oscillating piece is also chilled, and is designed to bear 65 against the chilled shaft or connecting-cylinder n of the double roller. The oscillating bearing S is connected to the lugs c by the pin d, which serves to keep the bearing S in position, while allowing a free movement of oscillation. In this construction the weight of the 70 car on the box is transferred to the axle-journal through the top bearing, B, interior oscillating piece, S, and the double roller; and it is apparent that, whatever be the relative positions of the axle-journal and box, the oscillating bearing will automatically accommodate 75 itself thereto in such a manner that the roller-bearings of the double roller will at all times fully engage the axle-journal.

80 In some instances it may be desirable to make the top bearing, B, concave circularly, so that it will have more bearing-surface upon the oscillating piece S. In this case the pin d should work in slots of sufficient size to allow 85 a free movement of the oscillating bearing, while controlling it against endwise thrust; and in other particulars the construction may be varied by those skilled in the art without departing from my invention.

89 It is obvious that the journal-box herein described is adapted for use upon passenger-cars, freight-cars, locomotives, and all shaft-bearings to which it can be applied.

95 What I claim, and desire to secure by Letters Patent, is—

1. In a car-axle box, the double roller L and a convex oscillating piece, S, operating in connection with said double roller, and with a plain bearing in the upper part of the box, 100 substantially as specified.

2. In a car-axle box, the combination, with

the lower submerged lubricating-rollers, G and H, provided with gear, substantially as shown, of the upper lubricating-rollers, E and F, the double rollers L, and means for securing parallelism between the said double rollers and the journal D, whereby the lubricating material may be raised in a positive manner and discharged on the journal and friction-rollers, substantially as specified.

In testimony whereof I affix my signature in presence of two witnesses.

RUSSELL BREWER.
